Primary Examiner — Catherine S Posthauer*Assistant Examiner* — Christine Marie Achen Zimmerman(74) *Attorney, Agent, or Firm* — Notaro, Michalos & Zaccaria P.C.**CLAIM**

The ornamental design for cookware with utensil retainer, as shown and described.

DESCRIPTION

FIG. 1 is a perspective view of a first embodiment of a cookware item with a utensil retainer showing our design.

FIG. 2 is a left elevation view of the same.

FIG. 3 is a right elevation view of the same.

FIG. 4 is a rear elevation view of the same.

FIG. 5 is a front elevation view of the same.

FIG. 6 is a top plan view of the same; and,

FIG. 7 is a bottom plan view of the same.

A second embodiment of our design is a mirror image of the cookware item shown in the Figures.

The broken lines are shown for the purpose of illustrating parts of the article that form no part of the claimed design.
